ILLUMINATING TONGUE DEPRESSOR WITH REPLACEABLE BLADE

Ladislav L. Edinger, 1084 Allerton Ave.,
Bronx, N.Y. 10469

Filed Oct. 7, 1971, Ser. No. 187,590

Term of patent 14 years

Int. Cl. D24—02; D26—04
U.S. Cl. D83—12

FIG. 1 is a perspective view of an illuminating tongue depressor with replaceable blade showing my new design, the blade element is separated from the unit for purposes of illustration;

FIG. 2 is a perspective view of the illuminating tongue depressor with replaceable blade in an operative position;

FIG. 3 is a side elevation;

FIG. 4 is a top plan view;

FIG. 5 is a bottom plan view;

FIG. 6 is a front elevation; and

FIG. 7 is a rear elevation;

I claim:

The ornamental design for an illuminating tongue depressor with replaceable blade, substantially as shown and described.
